UNITED STATES PATENT OFFICE.

PETER HORSLEV, OF CHICAGO, ILLINOIS.

WINDOW.

1,378,828.

Specification of Letters Patent.

Patented May 17, 1921.

Application filed November 22, 1919. Serial No. 339,812.

To all whom it may concern:

Be it known that I, PETER HORSLEV, a citizen of the United States, residing at Chicago, in the county of Cook and State of Illinois, have invented certain new and useful Improvements in Windows, of which the following is a specification:

My invention has reference more particularly to a window frame which is adapted 10 to utilize window sash of the usual construction and enable same to be readily removed from the frame for washing or cleaning.

The principal objects of the invention are, 15 to provide an improved window frame adapted to have a window sash readily removed therefrom or replaced therein; to provide a removable window structure utilizing standard window sash which are held 20 in place and releasable by an improved retractable structure forming a part of the window frame; to provide a removable window structure in which the window sash are rendered removable by a slight altera- 25 tion or change which is easily made in a standard form of window frame; to provide improved means for holding a section of the window frame so as to permit retraction thereof for the purpose of remov- 30 ing and replacing the window sash; and in general, to provide an improved removable window sash structure which is simple and inexpensive, and enables the window sash to be easily and quickly removed and 35 replaced, and wherein the improvement is capable of being applied to standard window frames already installed, by making a slight change therein.

On the drawings, 40 Figure 1 is a fragmentary front view of a portion of window casing or frame with portions of the upper and lower sash mounted therein;

Fig. 2 is an enlarged sectional view taken 45 through the entire window structure on the line 2—2 of Fig. 1;

Fig. 3 is a fragmentary sectional view of the device which I employ for affording a movable window channel, said view being 50 taken on the line 3—3 of Fig. 2;

Fig. 4 is a front view of the structure shown in Fig. 3;

Fig. 5 is a perspective view of the connector which I employ for fastening the 55 suspending cord or rope to the window sash;

Fig. 6 is a perspective view of a window frame with the lower sash swung inwardly and elevated and held at the top of the window frame;

60

Fig. 7 is a side view of the hanger for supporting the window in an elevated position;

Fig. 8 is an enlarged view of the bracket for supporting the hanger, taken on the 65 line 8—8 of Fig. 7;

Fig. 9 is a sectional view on the line 9—9 of Fig. 8;

Fig. 10 is a fragmentary top view of a bottom portion of the window frame and 70 the bracket mounted therein for holding the retractable channel strip;

Fig. 11 is a vertical sectional view on a plane coincident with the rear face of the combined strip 15—16, showing the manner 75 of mounting the lower end of said combined strip in the window frame; and

Fig. 12 is a sectional view on the line 12—12 of Fig. 11.

Referring to the drawings, the reference 80 numerals 1 and 2 indicate opposite side portions of a window frame, which frame, except as hereinafter noted, is similar to standard window frames which are now commonly used, each of said portions being constructed in a box-like form with a vertical shaft or weight well 3 therein, in which the window weights operate. There is a base or sill 4 at the bottom of the window frame with the usual window ledge 5 at the 85 inside, and the window opening in which the window frame is mounted is surrounded at the inner side by a casing consisting of side strips 6, and a top strip 7.

At each side of the window frame, a pair 90 of vertical parallel grooves or window channels 8 and 9 are formed for the lower and upper sash 10 and 11 respectively. These channels are formed by the inner and outer spaced strips 12 and 13, of molding, with a parting strip interposed therebetween, which is usually set into a recess in the side of the window frame, as shown at 14 in Fig. 2.

The structure so far described, and the 105 window sash 10 and 11, are of the usual standard form without change, except as follows: At one side of the window casing, for example the side indicated at 1 on the drawings, a section of the parting strip and 110 a corresponding section of the side frame which forms the base of the channel 8 oc-

cupied by the lower sash 10, is removed from a point at or adjacent the sill 4, and up to a point a short distance above the top of the sash 10, and a movable channel 5 base and parting strip section indicated at 15 and 16 respectively, of a length slightly greater than the vertical dimension of the sash 10, is mounted in place thereof so as to be retracted in the direction of the arrow 10 17 in Fig. 3, a sufficient distance to enable the window sash to be removed from the window frame. The channel base 15 and parting strip 16, are arranged to normally form a continuation of the corresponding 15 parts of the side 1 of the window frame and may, if desired, be constructed of the section of the parting strip, and section of the side frame which has been removed to make provision for the retractable section 20 15-16.

For mounting the section 15-16 in the side of the window frame the opening in the latter which is provided to accommodate the section 15-16 has brackets 18 and 65 25 at the upper and lower end respectively, which are similar in construction, reversely positioned, and each provided with spring arms connected with the ends of the strip 15, and exerting a tension to hold the combined strip 15-16 in normal position.

Each bracket, 18 and 65, comprises a face plate, which is flush with the bottom of the channel 8, and has a pair of spaced side wings 20 extending rearwardly therefrom, and connected together by a horizontal plate 21 which in the upper bracket 18 connects the upper edges of the side wings 20, and in the lower bracket connects the lower edges of the side wings. Each bracket 40 is provided with a pin 22 which extends between and is carried by the side wings 20, and has a coiled spring 23 thereon with an intermediate looped portion 24 which is connected with a hook 25 on the plate 21. The 45 opposite extremities of the spring 23 are provided with arms 26 which are spaced apart so as to be located adjacent the side wings 20, and the arms 26 of the upper bracket extend downwardly so as to embrace the upper end of the strip 15, whereas the arms 26 of the lower bracket extend upwardly to embrace the lower end of said strip. The ends of the strip 15 have opposite edge portions cut away, as indicated in 50 Figs. 3, 11 and 12, to form a pocket at each side to receive the arms 26 and afford a wide tongue 27 embraced thereby, and the ends of the arms are bent inwardly, as indicated at 28, and inserted in sockets 29 55 provided therefor at opposite sides of the strip 15 at a distance from the ends thereof. These spring arms 26 exert a tension to hold the combined strip 15-16 outwardly so that the ends of the strip 15 engage 60 65 against extensions of the face plates of the

brackets 18 and 65, the ends of the strip being notched, as indicated at 19, to admit the extension of the respective bracket, and permit the outer surface of the strip 15 to be brought flush with the outer surface of 70 the face plates of the brackets.

The brackets 18 and 65 are alike except that the former has the face plate extended upwardly as indicated at 30 in Figs. 3 and 4 to overlap the lower end of the portion of 75 the side frame directly above the opening in which the combined section 15-16 is mounted, and there is a screw 31 inserted through the extension into the side frame, and a screw 32 inserted through the plate 21 of 80 the bracket into the side frame of the window, whereas the lower bracket 65 merely has the lower plate 21 extended, as indicated at 33, and screws 64 are inserted through the extension 33 into the sill 4 for holding 85 the bracket 65 in place. I prefer to set the pin 22 as far away as possible from the face plate of the bracket to afford a space therebetween for inserting the screw 32 through the cross wall 21, as shown in connection 90 with the upper bracket in Fig. 3, and it is to be understood that a screw may be applied to lower bracket in a similar manner through the plate 21 if the connection of the extension 33 with the window sill 4 is deemed 95 insufficient.

For holding the combined strip 15-16 in either position of its adjustment, the parting strip 34 is provided at its lower end and somewhat distant from the front edge thereof, with a vertical aperture in which a locking bolt 36 is arranged to reciprocate, said locking bolt having a laterally projecting operating pin 37 passing through a vertical slot 38 and projecting at the front of the 105 parting strip in a finger groove 39 so that the locking bolt 36 may be manually operated.

A socket 40 is provided in the upper end of the movable parting strip 16, into which the lower end of the locking bolt 36 may be projected to lock the combined strip 15-16 in the normal position, and when the strip 15-16 is retracted, the lower end of the bolt 36 engages against the outer edge of 110 the movable parting strip 16 and holds the combined strip 15-16 in the retracted position. A similar locking bolt is mounted in the lower end of the movable parting strip 16, and the window sill 4 is provided 115 with apertures 41 and 41^a, the former of which is positioned to be engaged by the locking bolt for holding the combined strip 15-16 in the forward position indicated by dotted lines in Fig. 10 and by full lines in 120 Fig. 12, and the latter of which is arranged to hold the lower end of the combined strip 15-16 in the retracted position shown by dot and dash lines in Fig. 10.

The lower sash is designed to be first re- 125 130

5 moved and then elevated to permit convenient access to the other sash, the lower sash at such time having one edge engaged in one of the grooves 8 and being swung outwardly as indicated at 42 in Fig. 6. In order to 10 afford convenient detachable connection of the window weight cord 43 with the sash, I provide a cylindrical insert 44 of suitable size to fit in the socket 45 which is provided 15 in the edge of the window sash, and pass the rope 43 through an aperture 46 adjacent the outer end of the insert and secure a clip 47 on to the projecting end of the rope 43, to prevent withdrawal from the aperture 46. 20 This insert 44 fits in the socket 45 and there is the usual groove 48 on the edge of the sash above the socket 45 to accommodate the cord or rope 43.

25 For holding the sash in the elevated position shown at 42 in Fig. 6, I employ a removable hanger 49 which has a hooked outer end 50 adapted to engage the frame of the sash and there is a sliding clamp 51 on the hanger 49 which may be adjusted and locked 30 by a thumb screw 52 against the frame of the sash to hold same within the hooked portion 50 of the hanger. For mounting the hanger on the window casing, a plate 53 is secured to the top strip 7 of the casing, and has a flat 35 transverse slot 54 positioned so that the upper edge thereof is in the plane of the lower surface of the window frame as shown in Fig. 8, and the inner end of the hanger 49 is formed with a quarter turn so that the 40 flat end 55 may be inserted through the slot 54 under the upper surface of the window casing. The flat portion has a notch 56 which interlocks with one end of the slot 54 and there is a latch 57 pivoted at 58 on 45 the plate and formed with a shoulder 59 which engages the opposite edge of the flat portion 55 of the hanger, when the notch 56 at the opposite edge is engaged with the end of the slot 54 and thus locks the hanger in the slot 54 against accidental removal.

50 Each window is provided with a plate 53 for the hanger 49 and the window washer or cleaner carries a hanger 49 with him and mounts same temporarily on each window casing while he is working on the windows and removes same thereafter.

55 When it is desired to remove the window sash for washing or any other purpose, the lower sash 10 is raised sufficiently so that access may be had to the lower end of the combined strip 15-16 and the locking bolt 36 at the lower end of the combined strip is released from engagement with the aperture 41, the lower end of the combined strip 60 15-16 retracted, and the locking bolt engaged with the aperture 41^a so as to hold the lower end of the combined strip in retracted position. The sash 10 is then lowered to afford access to the upper end of 65 the combined strip 15-16 and the upper

end likewise retracted by releasing the bolt 36 and held in the retracted position. The sash 10 is then moved laterally to the right (looking at Fig. 1), the retracted strip 15-16 permitting such movement, until the 70 opposite or left hand edge of the sash is withdrawn from the groove 8 beyond the molding strip 12. The left hand side of the sash 10 may then be swung inwardly, as shown by the dotted line at 60 in Fig. 2, and 75 after it is swung past the molding 12, may be withdrawn from the retracted groove at the opposite or right hand side of the window frame. It is preferred after such removal, to re-insert the left hand edge of 80 the sash frame in the groove 8 and swing the right hand side of the sash outwardly, as shown by dotted lines at 61 in Fig. 6, whereupon access is had to the outer side of the window sash. When the sash is swung 85 to this position, the weight cord 43 is preferably detached therefrom by removing the insert 44 from the socket 45, and I provide a double hook 70 or any suitable fastener on the window frame or casing to which the 90 end of the cord 43 is secured when detached from the window sash. When the work is finished on the lower sash, it is elevated with the left hand edge remaining in the groove 8 to the position shown at 42 in Fig. 95 6, and the upper edge of the sash is then secured to the clamp 50-51 of the hanger 49 so that the sash is held in the elevated position during operations on the other sash.

100 The sash 11 is then lowered, and the right hand edge thereof moved inwardly past the retracted parting strip 16 to the position shown by dotted lines at 63 in Fig. 6. If necessary, the edges of the sash 11 may be 105 planed off as indicated by dotted lines at 71 and 72 in Fig. 2, to enable the edge of the sash to more readily clear the molding 12 as it is swinging inwardly.

110 In some windows, particularly those that are quite wide, the edge of the sash 11 may not pass the molding 12, and in such cases the sash is swung inwardly to the dotted line position 63 in the following manner: The right hand edge thereof is first moved 115 inwardly past the retracted parting strip 16, so as to engage in the retracted groove. The window is then pushed laterally to the right and withdrawn from the groove 9 at the opposite side thereof, and the left hand side of 120 the sash pushed outwardly, as shown by the dotted lines 62 in Fig. 2. The right hand side of the sash is then removed from the retracted groove and the window pulled inwardly through the window frame opening and the left hand side thereof reinserted in the groove 9 with the sash occupying a position shown by the dotted lines at 63 in Fig. 6, giving access to 125 the other side of the sash. The window 130

sash are re-inserted in place by reversing the operations just described for removing the sash from the window frame.

It will be observed that in my invention, 5 window sash of standard construction are employed without requiring any change whatsoever, except possibly planing off the edges at 71 and 72, and a standard window frame is used without any change except the 10 installation of the retractable strip 15—16 and this may readily be provided in a standard window frame by removing the corresponding portion of the frame and mounting the retractable strip in place thereof. 15 For mounting the said strip the latter first has the brackets attached to the ends thereof by means of the spring arms 26, and is then inserted in place in the window frame and the screw 31 inserted through the 20 tension plate 30 of the upper connector, and the screws 64 inserted through the extension 33 of the lower connector. The screw 32 may then be inserted by retracting the end of the strip 15 which enables a screw driver 25 to be inserted back of the face plate of the bracket to fasten the screw 32 in place.

While I have shown and described my invention in a particular form, I am aware that various changes and modifications may 30 be made without departing from the principles of my invention, the scope of which is to be determined by the appended claims.

I claim as my invention—

1. In a window frame, the combination 35 of a jamb having a channel on the outer face adapted to engage the edge of the window sash, and a longitudinal opening in the jamb at the bottom of the channel, and of sufficient length to allow the sash to be 40 moved edgewise therein, a movable jamb section closing the opening, a bracket on the frame at each end of the opening, and a spring mounted on each bracket and having spaced arms extending longitudinally 45 in the opening at opposite sides of the section, and engaged with the section at a distance from the ends so as to permit retraction of the section from the opening, and normally hold the section flush with 50 the bottom of the channel.

2. In a window frame, the combination 55 of a jamb having a channel on the outer face adapted to engage the edge of a window sash, and a longitudinal opening in the jamb at the bottom of the channel, and of sufficient length to allow the sash to be 60 moved edgewise therein, a movable jamb section closing the opening, a bracket on the frame at each end of the opening having a front plate extending in front of the opening, so as to be engaged by the end of the movable section, and a pair of spring

arms on each bracket embracing the respective end of the section and connected therewith at a distance from the end so as to 65 permit retraction of the section and normally hold the ends thereof against the front plate of the bracket.

3. In a window frame, the combination 70 of a jamb having a channel on the outer face adapted to engage the edge of a window sash, and a longitudinal opening in the jamb at the bottom of the channel and of sufficient length to allow the sash to be 75 moved edgewise therein, a bracket at each end of the opening having a cavity therein containing a spring which has arms extending into the opening, and a movable jamb section closing the opening and having the ends inserted between the arms of the 80 springs, and connected therewith so as to be retractable against tension of the springs and normally held thereby flush with the bottom of the channel.

4. In a window frame, the combination 85 of a jamb having a channel on the outer face adapted to engage the edge of the window sash, and a longitudinal opening in the jamb at the bottom of the channel and of sufficient length to allow the sash to be 90 moved edgewise therein, a bracket secured to the frame at each end of the opening, and each comprising a front plate with a pair of spaced side walls extending rearwardly in the opening, a stem extending between the side walls and having a coiled spring mounted thereon, said spring having a pair of spaced arms extending lengthwise of the opening and at opposite sides thereof, a movable jamb section closing the 100 opening and having reduced extremities interposed between the arms of the spring and connected therewith so as to be retractable against the tension of the spring and resiliently held thereby against the front plates 105 of the brackets.

5. In a window, the combination of a window frame having opposed walls with channels on the faces thereof, and a longitudinal opening in the base of one of the 110 channels of sufficient length to allow a sash to be moved edgewise therein, sashes mounted to slide in the channels, a movable section closing the opening means at each end of the opening for resiliently holding the 115 section in the plane of the wall, said means comprising fittings having springs adapted to be engaged on the ends of the sections and thereafter interposed between side walls of the opening so as to be confined between 120 said side walls and lateral faces of the section.

PETER HORSLEV.
